AIRPLANE AMUSEMENT DEVICE

Lawrence E. Reed, York, Nebr.

Application October 27, 1944, Serial No. 560,596

7 Claims. (Cl. 272—40)

1

This invention relates to an airplane amusement device, and has for one of its objects the production of a simple and efficient means for supporting and operating a plurality of vehicles simulating airplanes, in a manner whereby the vehicles will be easily controlled and whereby the amusement device will possess a maximum amount of safety.

Another object of this invention is the production of a simple and efficient means for rotatably supporting and bracing the operating tower.

A further object of this invention is the production of a simple and efficient means for automatically releasing the driving power from the operating tower when a predetermined rotation of the tower has taken place.

Other objects and advantages of the present invention will appear throughout the following specification and claims.

In the drawings:

Figure 1 is a side elevational view of the amusement device, certain duplicated parts being eliminated;

Figure 2 is a top plan view of the base of the device;

Figure 3 is a fragmentary enlarged transverse sectional view of the track-way and roller-supporting means for the tower;

Figure 4 is a fragmentary top plan view of one of the roller-supporting elements and track-way;

Figure 5 is a front elevational view of one of the roller-supporting elements;

Figure 6 is a side elevational view of one of the vehicles and suspending means therefor;

Figure 7 is a fragmentary top plan view of the driving mechanism and the supporting means for the tower, certain parts being shown in section;

Figure 8 is a fragmentary top plan view of the amusement device, certain parts being eliminated;

Figure 9 is a fragmentary side elevational view of the central supporting standard, a portion of the lifting jack also being shown;

Figure 10 is a fragmentary longitudinal sectional view of a portion of one of the extension arms, illustrating the latch therefor;

Figure 11 is a top plan view of one of the sweep-arms and bracing means;

Figure 12 is a top plan view of a portion of one of the sweep-arms, illustrating the connection between one of the sweep-arms and vehicles.

By referring to the drawings, it will be seen that 10 designates the platform-supporting base upon which is mounted a circular runway 11 preferably formed of a plurality of segmental

2

plates which are bolted or secured in any desired manner to the radiating bridge-work members forming the platform-supporting base near their outer ends. An inner circular track-way 12 is supported near the center of the converging bridge-work members forming the base 10 and these members are joined at their centers to a suitable spool or central connecting member 13.

The track-way 12 is bolted or firmly anchored upon the base 10, and carries upon its inner face a track rail 14 the upper and lower faces of which converge and extend inwardly at an angle of 45 degrees to the inner face of the track-way 12, as shown in detail in Figure 3. A tower T is supported upon the track-way 12 and comprises a plurality of upwardly extending posts 15 which converge toward the upper standard bracing guide 16 and are secured at their upper ends to this guide 16. The lower end of each post 15 is anchored to a roller-supporting shoe 17, as shown in detail in Figure 3. Each shoe 17 carries a pair of diverging rollers 18 which extend at diverging angles of 45 degrees to each other and freely roll upon the upper and lower faces of the rail 14. Each shoe 17 is provided with laterally extending flanges 19, connecting straps 20 being secured to these flanges 19 for connecting the respective shoes 17 in radial spaced relation, as shown in Figure 7.

30 A suitable ring gear 21 is secured to the inner faces of the shoes 17 and the flanges 19—see Figures 3 and 4. This ring gear 21 is engaged by a driving gear 22 which is driven by any suitable chain of gears from a source of power supplied 35 from a drive belt 23 through the pulley 24. The driving mechanism for the drive belt 23 may be controlled in any suitable manner. The pulley 24 is carried by a shaft 25 upon which is mounted a suitable clutch 26 which renders the cam wheel 27 selectively active or inactive at the will of an operator. Any type of clutch may be employed 40 for this purpose, without departing from the spirit of the invention.

45 A jack 28 of the conventional hydraulic type is carried centrally of the base 10 within the tower T and circular track-way 12. The jack 28 supports the overhead sweep supporting standard 29, and the standard 29 is adapted to be elevated as the pump 30 of the jack 28 is operated by the 50 rotation of the cam wheel 27, which wheel 27 is carried by the shaft 25—see Figure 3. The pressure from the jack 28 may be released by an operator actuating the conventional valve 30 from a suitable location of control.

55 The upper end of the standard 29 supports the

overhead sweep mechanism 31, which comprises a plurality of radiating sweep-arms 32. These arms 32 are braced by suitable guy braces 33 which are secured to the top of the standard 29, as at 34. The outer ends of the arms 32 carry a circular lamp reflector strip 32a upon which are mounted a series of lamps 35. The standard 29 carries a vertical key 36 which slides through the upper guide 16 of the tower T to permit vertical movement of the standard 29 and at the same time tie the parts together for unitary rotation.

A plurality of vehicles 38 simulating airplanes normally rest upon the circular run-ways 11 and are connected to the sweep-arms 32 by means of suspension chains 39, there being one sweep arm to each vehicle or airplane. The upper end of the chain 39 is connected to its companion arm 32 slightly inwardly of the vertical or perpendicular plane. An extensible bracing and propelling arm 40 is connected to each vehicle or airplane 38 and is hinged at its inner end to one of the uprights of the tower T as shown in Figure 1. A bracing chain 41 is connected to each arm 32 and to its companion propelling arm 40 just below to assist in relieving side strain upon the arms 40 and 32. The upper end 41a of each chain 41 extends to the next adjoining sweep-arm 32, as shown in Figure 8, in this way tying the sweep-arms 32 together near their outer ends. The latch 43 normally holds the extension rod 44 of the arm 40 in a set position, but as the arm 40 is swung upwardly, the latch 43 will be released by the pull upon the link 45 and permits the rod 44 to move outwardly of the arm 40 as centrifugal force causes the vehicle 38 to swing outwardly. As the parts return to their normal positions, the latch 43 will engage the rod 44 and latch the rod in the position shown in Figure 10. Each arm 40 is braced by a brace 40a, the brace 40a being connected at one end to the arm 40 near its outer end and the brace 40a is pivotally connected at its inner end to the next adjoining upright of the tower T. Cross-braces of a suitable type shown in Figure 11 are interposed between the arms 40 and their companion braces 40a to strengthen the parts.

It should be understood that a vehicle such as an airplane 38 is suspended from each of the sweep-arms 32, similar to the vehicle shown in Figure 1, and as the amusement device picks up speed, the centrifugal force will cause the vehicle or airplane 38 to be lifted from the runway 11. These vehicles are arranged in spaced relation radially around the tower T, and as the planes 38 revolve and gather momentum the rear tail wheel slowly lifts from the runway 11 until the plane is in a horizontal position with only the front wheels on the runway, thus simulating an airplane in its take-off. As the speed increases the entire plane rises well above the platform and at a selected height all of the planes are released and swing or fly outwardly due to centrifugal force, and as the arms 40 are swung upwardly the pull on the link 45 will release the latch 43 and permit the rod 44 to extend outwardly. When the power is cut off or the power is released from the sweeps 32, the planes will swing back to the normal positions as they slow down and will slowly descend until the front wheels strike the runway 11 followed by the rear wheels of the vehicle or plane 38. In this way, an airplane ride will be provided having features designed to break up the monotony of the usual merry-go-round ride, and the sensation to the occupants of the vehicles or airplanes will be similar to that

provided by an airplane in flight. Furthermore, in view of the fact that the vehicles or planes 38 normally rest upon the runway 11 they may be easily entered by children or others while the airplanes are at rest.

When the jack 28 elevates or lifts the standard 29, the load of the vehicles or planes 38 is carried by the lifting chains 39 and these vehicles will swing outwardly as the tower T rotates and gains momentum. However, when the vehicles 38 return to their normal position, so that they rest upon the runway 11, these chains 39 become slack and the arms 32 come into play and pull the vehicles 38 around the runway 11. These arms 32 are secured to the tower T in a manner as shown in detail in Figure 11 to brace themselves against the natural drag of the vehicle 38 on the platform or runway 11 as the vehicles are pulled around the runway 11.

It should be noted that the chains 41 which are connected to the arms 32 and 40 also at their upper ends span the distance between the arms 32 to tie these arms 32 together, as at 41a, to give rigidity to the sweep-arms 32. It should be further understood that the extension rod 44 of each sweep-arm 32 is of sufficient length to permit of a proper extension as the vehicles 38 are swung outwardly and at the same time enough of the rod 44 remains within the arm 40 to hold the extension rigid. When the vehicles 38 rest upon the runway 11 the chains 41 remain taut, but as the vehicles 38 rise and swing outwardly the outer ends of the arms 40 rise thereby causing the chains 41 to become slack. When the vehicles 38 again descend upon the runway 11, these chains become tight enough to be used as a bracing unit for all of the sweep-arms 40.

It should be understood that as the source of power is applied, the tower T revolves, carrying the vehicles 38 around the runway 11. The hoist is thrown into operation and when the vehicles rise to a predetermined position, the latches 43 automatically release the extension rods 44 permitting the vehicles 38 to swing to a flying position until the main driving clutch is released to allow the device to revolve free of the driving power and gradually come to a stop. The vehicles 38 will drop upon the runway 11 just before the device comes to a full stop. The lamp-carrying reflector strip 32a, the tower T, the vehicles 38 and connecting parts all revolve together. A suitable canopy may be carried over the reflector strip and tower if desired for decorative effect.

As shown in Figure 1, the post 15 of the tower T may be braced by means of suitable diagonal braces composed of turnbuckles and the like.

It should be understood that certain detail changes in the mechanical construction may be employed without departing from the spirit of the invention so long as such changes fall within the scope of the appended claims.

Having described the invention, what is claimed is:

1. An amusement device comprising a supporting tower, sweep-arms carried by and radiating from said tower, a runway surrounding said tower, driving means for rotating said tower, vehicles normally resting upon said runway, flexible means suspending said vehicles from said sweep-arms, said vehicles being adapted to be lifted and swung outwardly from said runway by centrifugal force created by the rotation of said tower, and radiating bracing arms secured to said tower and to the vehicles for assisting in moving the vehicles upon said runway.

2. An amusement device comprising a supporting tower, sweep-arms carried by and radiating from said tower, a runway surrounding said tower, driving means for rotating said tower, vehicles normally resting upon said runway, flexible means suspending said vehicles from said sweep-arms, said vehicles being adapted to be lifted and swung outwardly from said runway by centrifugal force created by the rotation of said tower, radiating bracing arms secured to said tower and to the vehicles for assisting in moving the vehicles upon said runway, and additional flexible means connecting the sweep-arms with said radiating bracing arms and also connecting the sweep-arms together.

3. An amusement device comprising a supporting tower, sweep-arms carried by and radiating from said tower, a runway surrounding said tower, driving means for rotating said tower, vehicles normally resting upon said runway, flexible means suspending said vehicles from said sweep-arms, said vehicles being adapted to be lifted and swung outwardly from said runway by centrifugal force created by the rotation of said tower, and radiating extension pivoted bracing arms secured to said tower and to the vehicles for assisting in moving the vehicles upon said runway.

4. An amusement device comprising a supporting tower, sweep-arms carried by and radiating from said tower, a runway surrounding said tower, driving means for rotating said tower, vehicles normally resting upon said runway, flexible means suspending said vehicles from said sweep-arms, said vehicles being adapted to be lifted and swung outwardly from said runway by centrifugal force created by the rotation of said tower, radiating bracing arms secured to said tower and to the vehicles for assisting in moving the vehicles upon said runway, additional flexible means connecting the sweep-arms with said radiating bracing arms and connecting the sweep-arms together, latch means for holding said bracing arms in a retracted position, and means for releasing said latch means when said bracing arms reach a predetermined position.

5. An amusement device comprising a supporting tower, sweep-arms carried by and radiating from said tower, a runway surrounding said tower, driving means for rotating said tower, 50

vehicles normally resting upon said runway, flexible means suspending said vehicles from said sweep-arms, said vehicles being adapted to be lifted and swung outwardly from said runway by centrifugal force created by the rotation of said tower, a standard vertically adjustable through said tower, said standard directly supporting said sweep-arms, means normally keying the standard and tower together, a lifting jack for vertically lifting said standard, and means co-operating with said driving means to automatically actuate said jack.

6. An amusement device of the class described comprising a base, a tower rotatable upon the base, a track-way carried by the base, a track-rail extending inwardly of the track-way, rollers carried by the tower and engaging the track-way above and below the track-rail for firmly holding the tower upon the track-way, a runway surrounding the track-way, vehicles normally mounted upon the runway, sweep-arms carried by said tower, means connecting said vehicles with the sweep-arms for lifting the vehicles from the runway as the tower rotates, and extensible 20 bracing arms connecting the vehicles to the tower.

7. An amusement device of the class described comprising a base, a track-way carried by the base, a tower rotatable upon the track-way, a plurality of shoes carried by the tower, a track-rail 30 carried by the track-way, rollers carried by said shoes engaging opposed faces of said track-rail for bracing said tower, a ring gear engaging said shoes, and driving means engaging the ring gear for rotating said tower.
